ATTORNEY

UNITED STATES PATENT OFFICE

THOMAS E. BRALY, OF LONG BEACH, CALIFORNIA

LONG-STROKE WALKING-BEAM ATTACHMENT

Application filed August 16, 1926. Serial No. 129,340.

As may be inferred from the above title, this invention relates particularly to means for increasing the vertical reciprocation of a pump rod, or the like, as produced by cyclical oscillation of a walking beam such as is commonly used in the pumping of deep wells.

It is well known that, in view of the crookedness of well holes, the elasticity of pump rods and the character of the fluid pumped, it is often difficult or practically impossible to utilize, at great depths, pumping organizations which are entirely adequate in the case of more shallow wells; and it is accordingly an object of my invention to provide means, suitable for installation in conjunction with or as a supplement to ordinary pumping rigs, for substantially increasing the length of a pumping stroke, suitably to the use of the mentioned equipment in deep wells; and preferred embodiments of my invention may comprise levers supported upon fixed pivots substantially parallel with walking beams and movable thereby,—one end of each of said levers being supported upon a rigid bracket or post, the opposite ends thereof being arcuate in form, and intermediate means being provided for the transmission of motion from a walking beam thereto.

Other objects of my invention, including the provision of a long stroke attachment in which a relative slowing at the respective ends of a reciprocating or oscillatory movement is incidentally provided for, and in which play-permitting means such as pin-and-slot connections are provided either at the points of support of the mentioned levers or at the point of connection of said levers with walking beams, a pair of like levers being preferably disposed on opposite sides of a walking beam and interconnected thereabove in such manner as to provide an equalizing yoke for the removable attachment of a flexible element used directly or indirectly in the reciprocation of a pump rod, may be best appreciated from the following description of an illustrative embodiment of my invention, taken in connection with the accompanying drawings, in which

Fig. 1 may be referred to as an elevational general view, with parts broken away.

Fig. 2 is a partial top plan view, taken substantially as indicated by the arrow 2 of Fig. 1.

Fig. 3 is a partial end elevational view, taken substantially as indicated by the arrow 3 of Fig. 1.

Figs. 4 and 5 are respectively sectional detailed views, taken substantially as indicated by the lines 4—4 and 5—5 of Fig. 1.

Referring to the details of that specific embodiment of my invention chosen for purposes of illustration, 11 may be a so-called bull post supporting a walking beam 12, reciprocatory movement being imparted to said walking beam in any usual or preferred manner, as by an adjustable pitman 13 secured thereto and to a crank 14 upon a shaft 15 provided with a bull wheel 16, or the like,—and the mentioned parts may be associated in any desired way with parts of a main frame comprising any desired uprights 17 and/or horizontal beams 18. The latter are shown as supporting a floor 19, through which may extend, or upon which may be supported, pump parts of any desired character, the reciprocation of the walking beam 12 being utilized directly or indirectly to impart movement to, for example, a so-called polish rod 20, which may be connected with a string of sucker rod for the operation of a reciprocatory pump in a known manner.

Coming now to the strictly novel features of my invention, instead of connecting the polish rod 20, or its equivalent, more directly with what I may term the pulling end 21 of a walking beam, I provide a fixed pivot or pivots 22 (as upon rigid brackets or posts 23) for an intermediate lever or levers 24,—a pair of like levers being shown as disposed upon opposite sides of said walking beam and as connected therewith by pin-and-slot connections, indicated at 25.

The levers 24 may respectively comprise arcuate sections 26, whose curvature may center in pivots 22,—assuming these to be the fixed pivots; and the upper ends of these arcuate sections may be rigidly interconnected by means such as a grooved or arch-like yoke member 27,—the sections 26 and the yoke 27 being alike provided with channels suitable

for the reciprocation and releasable retention of a cable 28, or the like. Whether or not the mentioned grooves permit a longitudinal slippage of the cable, it may be attached in any usual or preferred way (as by a gripping and equalizing member best shown in Figs. 1 and 3) to the polish rod 20, or its equivalent.

It will be appreciated that the brackets or posts 23 may advantageously be interconnected and secured by frame members 29, or the like; that the pivots 22 upon which the levers 24 are fulcrumed may be supported therefrom by bearing brackets 30 of any suitable design; and that slots 25^a through which extend pins 25^b, shown as secured by a fitting 31 to the walking beam 12 (pivoted at 32) may optionally be of such length as to permit of some variation in the ratio of the shorter arm of the lever 24 to the longer arm thereof, by, for example, a change in the position of the plate carrying coaxial pivots 22, and that, at mid-stroke, the pivots 22, 25^b and 32 may advantageously lie in a common horizontal plane.

From the foregoing, it will be obvious that, dependent upon the length of the longer arm of the lever 24, as compared with the shorter arm thereof, and dependent also upon the distance from the main pivot 32 of the walking beam 12 at which the pivots 22 are secured, and dependent also upon the point of insertion of wrist pin 33 on crank arm 34 (with a consistent adjustment of the turn-buckle 13) variations in the length of a pumping stroke may be produced; and also that, the distance between the pivots 22 and 25^b being least when the walking beam 12 occupies a substantially horizontal position, the motion imparted to a polish rod 20, or the like, by means of the general character described may be appreciably slowed at the ends of strokes produced by means of the general character described, this slowing being favorable to a reliable operation of the valves of the pump operated thereby.

Although I have herein described a single complete embodiment of my invention, it should be understood not only that various features thereof might be independently used but also that numerous modifications might be made by those skilled in the art to which this case relates, all without the slightest departure from the spirit and scope of this invention, as the same is indicated above and in the following claims.

I claim as my invention:

1. In a long-stroke organization for a deep well pump operated by means comprising a walking beam having a fulcrum intermediate of its ends pivoted on a bull-post: an intermediate lever having a fulcrum at one end thereof and movable in a plane substantially parallel with said walking beam, said lever being pivoted on a fixed support and provided with

flexible means for connecting a sucker rod therewith; and play-permitting means for transmitting motion from said walking beam to said lever.

2. In a long-stroke organization for a deep well pump operated by means comprising a walking beam pivoted on a bull-post: an intermediate lever movable in a plane substantially parallel with said walking beam, said lever being pivoted on a fixed support and provided with flexible means for connecting a sucker rod therewith; and play-permitting means for transmitting motion from said walking beam to said lever, said last mentioned means comprising a pin-and-slot connection between said beam and said lever.

3. In a long-stroke organization for a deep well pump operated by means comprising a walking beam pivoted on a bull-post: an intermediate lever movable in a plane substantially parallel with said walking beam, said lever being pivoted on a fixed support and provided with means for connecting a sucker rod therewith; and play-permitting means for transmitting motion from said walking beam to said lever,—a pair of said intermediate levers being disposed on opposite sides of said walking beam.

4. In a long-stroke organization for a deep well pump operated by means comprising a walking beam pivoted on a bull-post: an intermediate lever movable in a plane substantially parallel with said walking beam, said lever being pivoted on a fixed support and provided with flexible means for connecting a sucker rod therewith; and play-permitting means for transmitting motion from said walking beam to said lever, said last-mentioned means being positioned between said fixed support and said connecting means.

5. In a long-stroke organization for a deep well pump operated by means comprising a walking beam pivoted on a bull post; an intermediate lever movable in a plane substantially parallel with said walking beam, said lever being pivoted on a fixed support in substantially the same horizontal plane with the pivot point of said walking beam, and provided with means for connecting a sucker rod therewith; and play permitting means for transmitting motion from said walking beam to said lever.

6. In a long-stroke organization for a deep well pump operated by means comprising a walking beam pivoted on a bull post; an intermediate lever movable in a plane substantially parallel with said walking beam, said lever being pivoted on a fixed support in substantially the same horizontal plane with the pivot point of said walking beam, and provided with means for connecting a sucker rod therewith; and play permitting means for transmitting motion from said walking beam to said lever, said play permitting means com-

- prising a pin which at midstrokes of said lever, lies substantially in the horizontal plane containing the fixed pivot points of said walking beam and said lever.
- 5 7. In a long stroke organization for a deep well pump operated by means comprising a walking beam pivoted intermediate of its ends, an intermediate lever pivoted at one end on a fixed support and provided at the 10 opposite end with an arcuate member, said intermediate lever being arranged to operate in a plane substantially parallel with said walking beam, flexible means for connecting said arcuate member with a sucker rod, and 15 play permitting means for transmitting motion from said walking beam to said lever.

In testimony whereof, I have hereunto set my hand at Los Angeles, California, this 3rd day of August, 1926.
